HOLDER FOR LOOSE-LEAF SHEETS

Fred Cleiff, Palisades Park, N. J.

Application April 27, 1948, Serial No. 145,992

Term of patent 14 years

(Cl. D74—1)

To all whom it may concern:

Be it known that I, Fred Cleiff, a citizen of the United States, resident of the county of Hudson, Palisades Park, State of New Jersey, have invented a new, original, and ornamental Design for a Holder for Loose Leaf Sheets, of which the following is a specification, reference being had to the accompanying drawing, forming part hereof.

In the drawing,

The essential features of my new design are disclosed in full lines.

I claim:

The ornamental design for a holder for loose leaf sheets, substantially as shown and described.

FRED CLEIFF.
